UNITED STATES PATENT OFFICE.

WALKER MOSELEY, OF LONDON, ENGLAND, ASSIGNOR TO THE WESTERN ELECTRIC COMPANY, OF CHICAGO, ILLINOIS.

MULTIPLE SWITCH-BOARD.

SPECIFICATION forming part of Letters Patent No. 468,818, dated February 16, 1892.

Application filed December 26, 1888. Serial No. 294,576. (No model.)

To all whom it may concern:

Be it known that I, WALKER MOSELEY, a subject of the Queen of Great Britain, residing at London, England, have invented a certain new and useful Improvement in Multiple Switch-Boards, of which the following is a full, clear, concise, and exact description, reference being had to the accompanying drawings, forming a part of this specification.

10 My invention relates to that class of telephone-exchange systems in which the different lines are provided each with several terminals, these terminals being grouped upon different boards and so arranged that any 15 two lines of the exchange may be connected upon either of the switch-boards.

20 My invention relates more particularly to apparatus whereby when a line is once connected at one board the fact of such connection is made known to the operators at the other boards, in order that when two subscribers are connected upon one board they may not be interrupted at any other of the boards.

25 As to the state of the art prior to my invention reference is made to Letters Patent No. 266,320, granted Charles E. Scribner October 24, 1882, for telephone switch-boards and pneumatic signals therefor, and Letters Patent 30 No. 357,821, granted William S. Ford February 15, 1887, for multiple switch-board.

35 My invention consists in sliding bars, chain-toggles, and apparatus so arranged and connected between the different switch-boards that when a line is busy at one board the operators at other boards cannot insert their connecting-plugs to form connection with the same line. By this arrangement of apparatus I provide a mechanical test system which is 40 not dependent upon audible or visual indications, which have heretofore been considered indispensable.

45 My invention is illustrated in the accompanying drawings, in which—

Figure 1 shows three metallic-circuit telephone-lines, each connected with three different multiple switch-boards, with a different individual annunciator included in the circuit of each line. Fig. 2 shows three similar

50 metallic telephone-lines connected with three different multiple switch-boards and each including its individual annunciator, the switch-board apparatus being a modification of the apparatus shown in Fig. 1. Fig. 3 is a transverse vertical sectional view of the switch-board. Fig. 4 is a detailed sectional view of 55 one of the rollers or guides carrying the chain-toggles. Fig. 5 is a detailed sectional view of a connecting-plug inserted in a switch.

Like parts are indicated by similar letters 60 and numerals of reference throughout the different figures.

Referring to Fig. 1, *a* represents a metallic circuit, which may be traced to the metallic sleeve *b* of the switch on the first board, and 55 thence to the longitudinally-movable rod *c* and contact *d*, and thence through corresponding parts of the switch *e* of the line on the next board, and thence in the same manner through corresponding parts of the 70 switch *f* on the last board, and thence through annunciator *g*, and thence to the insulated thimbles *h i k* of the switches of the line on the different boards. The other metallic circuits *l m* are connected in the same manner 75 with their respective switches on the different switch-boards. The rod *c* of the switch of line *a* on the first board is shown in contact with the connection *d* of the switch. This is the normal position of the switches 80 when the lines are not connected or in use. When, however, a connection is made with a line, as shown at switch *n*, board 2, the longitudinally-movable rod *c'* is separated from its 85 normal contact *d'*.

The chain-toggle connection *o* extends across the switch-boards and is supported by guides *o'* on the different boards. The chain-toggle *o* belongs to the line *m*, and the guides or rollers *o'* are placed, respectively, on the 90 different longitudinally-movable rods of the switches of said line. The stops *o² o³* are fixed. Therefore, when a rod, as *c'*, is moved to the position shown, as is necessary when connection is made with the line, the guide *o'* of the sliding rod thus moved is forced against the chain-toggle between the stops *o² o³*, thus taking up all the slack in the chain-

toggle o , the chain-toggle o thus being drawn taut. It is now impossible to make connection with the same line at any other of the boards. If such connection were attempted, 5 it would be found that the longitudinally-movable rod of the switch of the line could not be moved far enough to admit of the attempted connection. Thus suppose an attempt were made to connect with line m at 10 switch p of board 1 the construction of the connecting-plug is such that in order to make a connection with any switch the sliding bar thereof must be moved, as shown at switch n . On attempting to move the sliding bar of 15 switch p the guide o , carried upon the sliding bar of switch p , would be obstructed by the taut chain-toggle o . The switchman on making attempt and finding the movement of the sliding rod obstructed would know that the 20 line was busy. This is essentially the mode of operation of my testing apparatus herein described and claimed.

I will now describe somewhat more in detail the different forms of the switch and the 25 form of the connecting-plug illustrated herein, it being, however, understood that the form of the switch, as well as that of the plug, might be modified in various ways without departing from my invention.

30 As shown in Fig. 1, each switch—as, for example, switch n —consists of a movable part c' , which I have termed the “sliding rod,” a contact-point d' , a spring p' , tending to hold said movable rod against the contact-point d' . The rod c' is supported by the metallic sleeves or sockets $p^2 p^3$ on the different sides, respectively, of the switch-board. (For detailed section of front socket p^3 see Fig. 5.) The sleeves $p^2 p^3$ are thus electrically connected whatever may be the position of the rod c' . The contact d' is placed at the rear of the board and is readily accessible. The thimble p^4 is insulated from the socket p^3 , as shown in Fig. 5. The different connecting- 45 plugs are each provided with two terminals, the tip or central terminal p^5 being adapted to be inserted in the socket p^3 to move the sliding bar c' to the position shown. The outer terminal p^6 of the plug is adapted to be 50 locked to the thimble p^4 , as shown, so that the plug when inserted may be held in place against the pressure of spring p' . I preferably use a bayonet-lock between the thimble p^4 and the terminal p^6 of the plug. Any other 55 form of locking device capable of doing the work might, however, be employed.

In Fig. 2 I have shown a single-circuit breaking and closing device in each line instead of a separate device for doing this work 60 in connection with each switch of each line. These circuit-closing devices $q q' q^2$ (illustrated in Fig. 2) are connected, respectively, with the chain-toggle devices $r r' r^2$. When a plug is inserted in a switch of any line upon 65 either board, the chain-toggle device, cord, or wire, as r , r' , or r^2 , is operated to open the key

q, q' , or q^2 , as the case may be. Thus, as shown in Fig. 2, plug s being connected with the switch s' , the key q^2 is drawn away from its normal contact to the position shown and 70 held while the connection remains. Thus by the apparatus shown in Fig. 2 one circuit-breaking device only in each line is required.

I do not consider it necessary to illustrate or describe the manner of connecting the telephone-lines with the subscriber's stations; neither have I deemed it necessary to illustrate or describe the operator's outfit in detail. It will be understood, however, that each line includes one or more subscribers' 80 stations. It will be also understood that an operator is placed at each board and provided with pairs of plugs and cords adapted to be connected with her telephone outfit and to loop the different lines together. The individual annunciators will be distributed upon the different switch-boards and suitable signaling apparatus provided, all in the usual manner.

Having thus described my invention, I 90 claim as new and desire to secure by Letters Patent—

1. The combination, with two or more switch-boards with which telephone-lines are connected, of chain-toggle devices, one for each 95 of the telephone-lines, each of said chain-toggle devices being drawn taut by the insertion of a plug in any switch of the line corresponding thereto to lock the other switches of said line on the other boards out of employment, substantially as and for the purpose specified.

2. A chain-toggle device extending across each of the two or more multiple switch-boards and being attached or supported upon the 105 movable part of a switch of each of said boards, in combination with the two or more multiple switch-boards and a connecting device or plug which on being inserted in either of said switches forces the movable part of the switch 110 in which it is inserted against the chain-toggle joint, thereby changing the tension of said chain-toggle device and obstructing the movement of the movable parts of said other switches, substantially as and for the purpose 115 specified.

3. A telephone-line connected with several switches, each on a different switch-board, said line including an individual annunciator placed between different sockets or guides, as 120 $p^2 p^3$, of the switch on the last board, the movable parts of the switches of the line being mechanically connected, in combination with a loop-plug inserted in one of said switches to open the connection of the line with the annunciator, while at the same time the other switches of the line are obstructed to prevent any other connection with the line, substantially as and for the purpose specified.

4. The switch consisting of the sliding bar, 125 with metallic sockets or guides therefor, one on each side of the board, in combination with

the insulated thimble on the face of the board around the front socket or guide, one branch of a line connected with the rear socket and the other branch connected with the thimble, and a loop-plug inserted in said switch to form connection with the said sliding bar and thimble, as described.

In witness whereof I hereunto subscribe my name this 3d day of December, A. D. 1888.

WALKER MOSELEY.
